UNITED STATES PATENT OFFICE.

JAMES L. RILEY, OF PHILADELPHIA, PENNSYLVANIA.

DESIGN FOR A STEAM-GENERATOR SECTION.

SPECIFICATION forming part of Design No. 27,216, dated June 15, 1897.

Application filed April 30, 1897. Serial No. 634,653. Term of patent 7 years.

To all whom it may concern:

Be it known that I, JAMES L. RILEY, a citizen of the United States, residing in the city and county of Philadelphia, in the State of Pennsylvania, have invented and produced a new and original Design for Steam-Generator Sections, of which the following is a specification, reference being had to the accompanying drawings, forming part thereof.

My invention relates to and comprehends a design for a generator section for employment as one of the sections of a steam generator composed of a series of assembled sections.

In the drawings,

Figure 1 is a view in side elevation of the section.

Figure 2 is a vertical, sectional elevation taken on the line 2—2 of Figure 1.

Figure 3 is a sectional plan taken on the line 3—3 of Figure 1.

As shown in the drawings, the leading and principal feature of my design consists of a hollow section of a general arciform outline, when viewed in side elevation, having a top A, a front member B and a rear member C, said members B and C being continuous of said top A, and being in communication with each other through two water legs D E, in line one beneath the other beneath the said top A,—the top member A, and the water legs D E, having the sectional configuration plainly illustrated in Figure 2 of the draw-

ings, and the members B C having the sectional configuration clearly shown in Figure 3 of the drawings.

F is a bead formed on one face of the top A and members B C, and following the marginal configuration of the section, and G is a groove formed on the opposite face of said top and members, and following a course corresponding to that of the bead.

Apart from the groove and bead, the respective faces of the section are counterparts.

The top A has the region *a* elevated above the normal level of the face of said top; the members B C have the regions *b c* raised above the normal level of the faces of said members; and the water legs D E have the regions *d e* raised above the normal level of the faces of said water legs,—the tops or crests of the several elevated regions or portions named, existing in a common plane.

Having thus described my invention, what I claim, and desire to secure by Letters Patent, is—

The design for a section for a steam generator, herein shown and described.

In testimony that I claim the foregoing as my invention I have hereunto signed my name this 22d day of April, A. D. 1897.

JAMES L. RILEY.

In presence of—

F. NORMAN DIXON,
THOS. K. LANCASTER.
